GRINDING MACHINE

Philip R. Hoffman, Carlisle, Pa., assignor to
Grover C. Hunt, Carlisle, Pa.

Application December 6, 1941, Serial No. 421,999

4 Claims. (Cl. 51—161)

This invention relates to grinding machines of the type generally known as lapping machines and, more specifically, relates to lapping machines which are particularly intended for the grinding of polygonal, relatively thin devices or articles such as piezo-electric crystals.

It has heretofore been proposed, and is now known, to provide a lapping machine in which externally geared, disc-like work holders are disposed between two superposed abrasive discs and are geared to an inner rotating pinion which is located centrally of the discs and to a ring gear which surrounds and is concentric with the pinion, either the pinion or the ring gear being rotated to cause the work holders to describe a planetary movement about the centers of the discs and, simultaneously, to rotate about their respective axes. The articles carried by the work holders are thus caused to move in either an epicycloidal or hypocycloidal path across the faces of the discs.

It is an object of the invention to provide a method and means, in a lapping machine of the type in which the work holders move in a planetary path and simultaneously rotate about their respective centers, to cause the articles being ground to follow a non-cycloidal path in which they will be swept circumferentially of the discs throughout their movement, thereby providing an improved grinding action.

It is also an object of the invention to provide a machine which is particularly useful and advantageous in the difficult and exacting work of grinding piezo-electric crystals.

Means for effecting these objects, as well as other objects of the invention, will be made apparent by the following description and the annexed drawings, it being understood that the description and drawings are only illustrative of the invention, for the limits of which reference must be had to the appended claims.

Referring to the drawings, in which the same reference numerals and letters refer to like parts,

Fig. 1 is a vertical sectional view of a machine according to my invention, taken on line 1—1 of Fig. 2;

Fig. 2 is a plan view of the machine of Fig. 1, taken on line 2—2 of Fig. 1, and

Fig. 3 is a schematic view of one of the discs, showing the typical path of an article being ground when my invention is employed.

A machine embodying the features of my invention is disclosed in the drawings. Thus, as shown in Fig. 1, the machine comprises a base or standard 2 which supports a lower abrasive disc 4 gg

which is fixed against movement, as by rigid attachment to the base. The lower disc is provided with a preferably circular central opening within which is disposed a pinion gear 6 which may be driven by any suitable means such as the pulley and belt 8. The gear 6 extends substantially above the upper surface of the lower disc. Surrounding the disc 4 is a ring gear 10 which is provided with internal and external teeth 12, 14 respectively, it being noted that the pinion gear 6 and ring gear 10 are concentric. The ring gear 10 is mounted for rotation and is supported by bearings 16 which engage the lower surface of an annular flange or cover 18 which is connected to the upper surface of the ring gear. A driving gear 20 engages the external gear teeth 14 of the ring gear 10 and, in order to rotate the ring gear, may be driven by suitable means such as the pulley and belt arrangement 22. An upper abrasive disc 30, which is substantially identical with the lower disc is attached to a cover 32 and is adapted to be received within the ring gear, whereby the abrasive faces of the two discs are opposed and will be in engagement with each other unless the crystals or the work holding means which are described hereinafter are interposed between them. The cover 32 is provided with openings within which a fixed pin, such as 34, may be received in order to prevent rotary or other movement of the upper disc. The cover may also be provided with handles 36 whereby it and the attached upper disc may be lifted. The upper disc and the cover therefor are preferably provided with a central opening which receives the upper portion of the pinion gear 6. Between the two discs are provided circular work holders 50 each of which is provided with gear teeth on its external periphery and is of such size that the gear teeth thereon engage those on the pinion gear 6 and the internal teeth 12 of the ring gear. Openings 52 are provided in each work holder, within which the crystals are received and held during movement of the work holders.

In accordance with my invention, the pinion gear 6 and the ring gear 10 are both rotated, both being rotated in the same direction and the pinion gear being preferably rotated at a greater speed in R. P. M. than the ring gear. I have found that if the pinion gear is rotated at 28 R. P. M. and the ring gear at 8 R. P. M. very good results may be obtained in the grinding of piezo-electric crystals. By reason of the rotation of both gears in the same direction and at different speeds the work holders will move in such a way that a crystal carried thereby will follow a wide, sweeping path

over the faces of the discs, by reason of the fact that the slower rotation of the ring gear in the same direction as the pinion permits only a very slow rotation of the work holder about its own axis. A typical path of a crystal held by the work holder is illustrated in Fig. 3, this path being produced by rotation of the pinion gear and the ring gear at the specific speeds mentioned hereinbefore. By reason of this movement the grinding action on the crystals is improved and the wear on the abrasive surfaces is made more uniform.

It will be seen, by reference to Fig. 3, that the path followed by a crystal when ground in a machine constructed and operated in accordance with this invention follows long, sweeping, overlapping lines having large circumferential components. The radial travel from the outermost periphery to the innermost periphery, as between points *a* and *b* in the direction of the arrow, requires a travel of almost one-half of the circumference of the discs. These lines of travel, overlapping as shown in Fig. 3 cause the entire faces of the discs to be traversed by the crystals being ground, thus causing completely even wear of the surfaces of the discs, whereby the character of the grinding is improved and the life of the discs prolonged.

While I have described my invention with reference to the grinding of crystals, it will be understood that the invention is of general application and is not limited to the grinding of any particular materials or devices. It will also be understood that while I have described my invention with reference to a machine having fixed, horizontal, vertically-spaced abrasives, it may without departing in any way from the invention be applied to other types and constructions of grinding machines.

Although only one form of the invention is illustrated and described in this application, it will be understood by those skilled in the art that modifications and improvements may be made without departing in any way from the spirit or

scope of the invention, for the limits of which reference must be had to the appended claims.

I claim:

1. A lapping machine comprising a pair of opposed abrasive discs, a pinion gear at the center of said discs, a ring gear concentric with said pinion gear and surrounding said discs, a plurality of externally geared work holders between said discs and arranged in a series about the pinion gear and being geared to said pinion and ring gear, and means for rotating both said pinion gear and ring gear.

2. A lapping machine comprising a pair of opposed abrasive discs, a pinion gear at the center of said discs, a ring gear concentric with said pinion gear and surrounding said discs, a plurality of externally geared work holders between said discs and arranged in a series about the pinion gear and being geared to said pinion gear and ring gear, means for rotating the pinion gear, and means for rotating the ring gear at a speed in R. P. M. less than that of the pinion gear.

3. A lapping machine comprising a pair of opposed abrasive discs, a pinion gear at the center of said discs, an internal ring gear concentric with said pinion gear and surrounding said discs, a plurality of externally geared work holders between said discs and arranged in a series about the pinion gear and being geared to said pinion gear and ring gear, and means for rotating both the pinion gear and the ring gear at different speeds in R. P. M.

4. In the grinding of articles by machines of the type comprising two opposed abrasive discs, a pinion gear disposed at the center of the discs, a ring gear disposed concentrically of the pinion gear and surrounding the discs, and a work holder disposed between the discs and having external gear teeth meshing with those of the pinion gear and the ring gear, the method of causing articles held by the work holder to move over the discs which consists in rotating the pinion gear and rotating the ring gear at a speed in R. P. M. which is less than that of the pinion gear.

PHILIP R. HOFFMAN.
